FRANK SCHNEIBLE, OF NEW YORK, N. Y.

BOTTLE CLOSURE

Application filed January 26, 1928. Serial No. 249,536.

The object of this invention is to provide for bottles which have a bead about the mouth and are commonly used for beverages, a temporary closure which can be applied to a bottle after it has been opened by the removal of 5 the cap, for the purpose of closing the bottle again after a portion of the contents has been removed and so preserving the remainder for future use. Various closures have been devised heretofore for such purposes and the 10 special object in view in this invention has been to produce an improved closure which can be manufactured at a reasonable cost, shall be so constructed that it can be used repeatedly without losing its efficiency, and 15 shall make it possible for every bottle with which it is used to be closed tightly against admission of air or leakage of the contents or escape of gas with which the contents may be charged. The improved closure is also 20 constructed in such manner that it can be applied or removed quickly. The improved closure comprises one main part which can be applied readily to a bottle of the kind referred to, and, 25 in the simplest form of the invention, a second part which is pivoted eccentrically upon the first part and is adapted by a swinging movement on a pivot to engage the bottle neck at a diametrically opposite point. The 30 first part is formed to carry a sealing disc of cork or other suitable material and means may also be provided for drawing and locking the two parts tightly together. The invention 35 will be more fully explained hereinafter with reference to the accompanying drawing in which:

Figure 1 is a view of the improved closure as seen from above, with the two parts or members in closing relation.

40 Figure 2 is a view in sectional elevation, the plane of section being indicated by the broken line 2—2 of Figures 1 and 3 and a portion of the bottle being also shown.

45 Figure 3 is a view generally similar to Figure 1 but with the two parts or members in open relation and with the pivot in horizontal section, the coned nut being removed.

50 Figure 4 is a view similar to Figure 2, but with the coned locking nut raised.

Figure 5 is a top view of the swinging member.

Figure 6 is a view of the swinging member in elevation as seen from the right hand in Figure 1.

Figure 7 is a top view of the main or base 55 member.

Figure 8 is a view in side elevation of the main or base member.

The improved closure has been designed 60 with particular reference to its use for the temporary closing of a bottle the neck *a* of which has at its mouth a lip or bead *a*¹.

The main or base member *b* is preferably 65 formed as a flat disc with a depending flange *b*¹. It is also formed, opposite the flange *b*¹, with a depending flange *b*² which is turned in at its lower edge in order that it may engage the lip *a*¹ of the bottle mouth, as clearly shown in Figures 2 and 4. It may also be provided 70 with projecting portions, as at *b*³ and *b*⁴, as finger pieces for the convenience of the user. In the construction shown the finger piece *b*³ is formed by cutting out and bending up a portion of the flange *b*² between its ends, 75 while the finger pieces *b*⁴ are formed by bending outward the ends of the flange *b*². Within the flanges *b*¹ and *b*² the member *b* may receive a sealing disc *c* of cork, rubber, or other suitable material which, in the operation of 80 the closure, is drawn down tightly upon the mouth of the bottle to close the same effectively.

The other part or swinging member *d* is 85 pivoted upon the member *b* at a point at one side of the center of the member *b*, as at *e*, and, being generally triangular in shape, is provided opposite the pivot *e* with a depending flange *d*¹ which is turned inward at its lower edge for engagement with the bead *a*¹ 90 of the bottle neck, as shown in Figure 2. The inturned edge of the flange *d*¹ is cammed, being wider at its following end than at its leading end, as shown in Figures 1, 3 and 5, so that when the closure has been applied to the bottle neck, as shown in Figure 3, and has been 95 swung from the position shown in Figure 3 to the position shown in Figure 1, the cammed edge portion *d*² of the flange shall draw the two parts of the closure tightly against the 100

bottle neck. The inturned lips b^2 and d^2 in coaction with the lower side of the lip a^1 of the bottle neck, when the parts are properly proportioned, serve to draw the sealing disc c tightly against the bottle mouth.

The swinging member d may be provided with finger pieces d^3 and d^4 for convenience in manipulation.

For many purposes as thus far described it is adequate, but in some cases it may be desired to provide additional means for drawing and locking tightly together the two parts of the closure. For this purpose the swinging member d is formed with an elongated slot d^5 to straddle the base of the pivot pin e and is also provided, at the back of such slot, with an upturned and outwardly flared lip d^6 and the pivot pin e is extended upward and threaded, as at e^1 , to receive a coned thumb-nut f . When the closure as thus provided is to be applied to the bottle neck the thumb-nut f is first backed off, as shown in Figure 4, to permit the closure to be applied to the bottle neck. Then, when the swinging part d has been swung to the closing position shown in Figures 1 and 2, the thumb-nut f is turned down and, engaging with the flared lip d^6 , draws the swinging member to the left, in Figures 1, 2 and 4, thereby drawing the lip d^2 tightly against the bottle neck and holding the closure tightly in position. This action also takes care of variations in size of bottle necks and heads and locks the closure against accidental release.

It will be observed that the improved closure has no parts which must be sprung upon or from the bottle neck, with consequent danger of breakage and of loss of efficiency, besides requiring the use of metal which has the required degree of resilience, that the closure is easily applied and when applied is securely held in position, with the bottle mouth tightly closed, and that the closure can be formed for the most part, at least, by stamping and therefore is inexpensive to manufacture.

It will be understood that the form and arrangement of the parts may be changed to suit bottles of one make or another, or of one size or another, and that the invention, therefore, except as pointed out in the accompanying claims, is not restricted to the particular construction shown and described herein.

I claim as my invention:

1. A bottle closure comprising one member formed to engage a bottle neck, a second member also formed to engage the bottle neck but opposite the first, a pivot pin secured upon the first member eccentric with respect to the center thereof and extended upwardly and threaded, the second member being formed with an elongated slot to engage the pivot pin and with an upturned flange, and a coned nut threaded upon the pivot pin and coacting with the upturned flange of the sec-

ond member to draw the flange of the second member tightly toward the flange of the first member.

2. A bottle closure comprising one member formed with a depending flange to engage a beaded bottle neck, and a second member also formed with a depending flange to engage the bottle neck but opposite the first and eccentrically pivoted upon the first to swing in the same plane therewith, the flange of the second member being turned in at its lower edge and a cam on the inturned edge to provide a positive means for gradually decreasing the distance between the inturned edge and the depending flange of the first member on the opposite side of the bead of the bottle as the second member is swung to a closed position.

3. A bottle closure comprising one member formed with a depending flange to engage a beaded bottle neck, and a second member also formed with a depending flange to engage the bottle neck but opposite the first and eccentrically pivoted upon the first to swing in the same plane therewith, the flange of the second member being turned in at its lower edge, a cam on the inturned edge to provide a positive means for gradually decreasing the distance between the inturned edge and the depending flange of the first member on the opposite side of the bead of the bottle as the second member is swung to a closed position, and means for locking the two members at any point in the closing position of the cam.

4. A bottle closure comprising one member formed with a depending flange to engage a beaded bottle neck, and a second member also formed with a depending flange to engage the bottle neck but opposite to the first and eccentrically pivoted upon the first to swing in the same plane therewith, the flange of the first member being turned in at its lower edge and the flange of the second member also being turned in at its lower edge, a cam on the inturned edge of the second member to provide a positive means for gradually decreasing the distance between the inturned edges of the depending flanges of the two members on opposite sides of the bead of the bottle as the second member is swung to a closed position, and means for varying the working radius of the cam.

5. A bottle closure comprising one member formed with a depending flange to engage a beaded bottle neck, and a second member also formed with a depending flange to engage the bottle neck but opposite to the first and eccentrically pivoted upon the first to swing in the same plane therewith, the flange of the first member being turned in at its lower edge and the flange of the second member also being turned in at its lower edge, a cam on the inturned edge of the second member to provide a positive means for

gradually decreasing the distance between the inturned edges of the depending flanges of the two members on opposite sides of the bead of the bottle as the second member is swung to a closed position, means for varying the working radius of the cam, and means for locking the closure members in any position.

5. A bottle closure comprising one member formed to engage a bottle neck, a second member also formed to engage the bottle neck but opposite the first, a pivot pin secured upon the first member eccentrically with respect to the center thereof and extended upwardly, a connection between the pivot pin and the second member permitting translatory as well as pivotal movement of the second with respect to the first, and means to impart translatory movement to the second member with respect to the first.

10. This specification signed this 25th day of January, A. D. 1928.
